SAND ROLL AND CLOTH ROLL MECHANISM

Fritz B. Peterson, Hopedale, Mass., assignor to
 Draper Corporation, Hopedale, Mass., a corpora-
 tion of Maine

Application May 7, 1949, Serial No. 91,903

16 Claims. (Cl. 139—308)

1

This invention pertains to certain improvements in looms for weaving, and more specifically, to improvements in sand roll and cloth roll mechanisms of the type wherein the woven fabric is wound upon a cloth roll by contact with a positively driven sand roll.

It is a general object of the invention to simplify and to eliminate considerable of the present structure to be found at the front of looms and which enters into the sand roll and cloth roll combination, such for example, as the conventional spring shaft and cloth roll stand at the base of the loom and adjacent the front thereof, and to provide improved means for more effectively accomplishing the same result.

It is a further object of the invention to provide for winding much larger rolls of fabric by eliminating the above mentioned structure at the front and adjacent the lower part of the loom framework and to leave more of that section of the loom frame unobstructed to facilitate servicing and removal of the completed rolls of woven material.

A further object of the invention is that of simplifying the cloth roll supporting stand and confining the parts thereof to a small space at the sides of the loom framework so that cost of manufacture and maintenance thereof may be considerably reduced.

Another object of the invention is that of devising a combined sand roll and cloth roll device in which the supporting shaft for the sand roll performs other functions. In addition to serving as a member upon which the sand roll may be positively rotated, it also replaces the usual spring shaft to be found at the lower part of the loom frame structure and controls the suspension system for the cloth roll and material wound thereon.

A further object of the invention is that of devising a positively driven hollow sand roll in which is enclosed most of the mechanism incidental to maintaining the cloth roll and fabric carried thereon in an elevated position and in pressure contact with the sand roll to assure proper winding of the fabric as it is drawn from the point of weaving.

A still further object of the invention is that of devising improved means for biasing the cloth roll toward the sand roll for the purpose above mentioned, which may be adjusted to provide any desired pressure between the fabric and sand roll and which needs no attention at periodic intervals as the roll of fabric is increased in size.

It is a further object of the invention to arrange the combined sand roll and cloth roll

2

mechanism more accessibly and to facilitate the servicing thereof.

A further object is that of improving the means and simplifying the method by which the sand roll covering is applied to the sand roll.

Other objects of the invention will be apparent from the following detailed disclosure.

In conventional sand roll and cloth roll mechanisms it is the usual practice to provide a sand roll adjacent the upper and front portion of the loom framework which is of substantially solid construction and which is mounted on a shaft carried in suitable bearings and driven in any satisfactory way from other rotating parts of the loom. The cloth roll which generally comprises a cloth roll shaft or core upon which the woven material is wound, is supported in what is termed a cloth roll stand comprising, among other parts, upright stands adjacent either end of the loom. The cloth roll shaft is maintained in an uppermost position as determined by the size of the roll of fabric on the cloth roll shaft at any particular time, by a spring shaft and cooperating parts adjacent the lower portion of the loom. One example of such mechanism is to be found in United States Patent 2,437,367. The spring shaft and devices for tensioning the rather heavy spring carried thereby are all located on a girt at the lower front portion of the loom and their position makes it rather difficult to effect adjustments as is essential when the cloth roll stand is to be elevated preparatory to starting a new roll of material, or whenever tension is to be relaxed in the spring, that frequently being necessary at intervals throughout the period of winding a complete roll and also, when doffing a roll.

The stand structure is relatively expensive since it requires racks, gears and relatively heavy vertical guide members within which the racks are carried, all of these adding to the cost of the installation and also adding to the weight of the complete machine and restricting the space available for winding and servicing a roll of material as large as is sometimes desired.

According to the invention the above mentioned mechanism is greatly improved and the more undesirable characteristics of the conventional structure eliminated. The improvements hereinafter to be described in detail involve a combination in which the support for the sand roll serves not only as a member upon which that particular roll may be positively rotated at the desired rate of speed, but also as a means of support for certain elements rotatable with the supporting shaft itself and employed for winding thereon or otherwise taking up or ex-

tending flexible elements such as cables from which the cloth roll bearing members are suspended. These bearing members or bearing blocks are of relatively simple construction, cheaply produced, and are adapted to slide to and from the sand roll upon very simple track means attached to the loomsides themselves, or on supplementary structural elements adjacent thereto. This sand roll supporting shaft also carries, preferably enclosed within the sand roll itself which is of hollow construction, an improved spring shaft mechanism by means of which the cloth roll is continuously biased or urged in a direction to establish the requisite pressure contact between the fabric wound on the cloth roll and the adjacent surface of the sand roll itself.

The spring shaft mechanism, so-called, may comprise a relatively simple, elongated coil spring and means for fixing one end to the shaft and other means within which the opposite end is restrained, this other means being capable of movement in such a manner as to vary the tension in the spring itself and to lock the restrained end of that spring in that adjusted position in which it is desirable that it be maintained. A preferred form of mechanism, however, comprises a clutch, one member of which is restrained from rotation relatively to the shaft, and the other member of which is rotatable on the said shaft. One of these clutch members is restrained from movement lengthwise of the shaft while the other is resiliently pressed into engagement with its companion clutch part so that frictional surfaces thereof impart a driving force or a retarding force, as the case may be, to the shaft and parts carried thereby which function therewith for biasing of the cloth roll as above mentioned. The freely rotatable clutch member has connected thereto in some suitable way one end of a spring, the other end of that spring being restrained in mechanism similar to and performing the same general function as that just above described with respect to the simpler form of spring shaft means.

The invention will be described hereinafter by reference to the accompanying figures of drawing wherein one preferred form of the invention and a modification are illustrated and in which:

Fig. 1 is a front elevation showing in a more general way the manner in which the invention is applied to a conventional loom.

Fig. 2 is a longitudinal section through the sand roll and attendant parts according to the preferred form which the invention takes.

Fig. 3 is a view similar to that of Fig. 2, but showing a modified and simpler form of the invention.

Fig. 4 is a front elevation of a fragmentary part of the loom showing details incidental to tensioning the cloth roll biasing means, and also the manner in which the sand roll supporting shaft may be carried in the loom framework.

Fig. 5 is an elevation taken from the end of the machine and further illustrating those parts shown in Fig. 4.

Fig. 6 is a sectional view showing in detail one of the cable sheaves employed at the ends of the sand roll supporting shaft and to which the cable is fixed and about which it may be wound and unwound incidental to raising and lowering the cloth roll bearings.

Fig. 7 is a section taken at the line 7—7, Fig. 6.

Fig. 8 is a perspective view showing one of the bearing blocks for the cloth roll shaft and a part

of the track upon which it is guided and along which it is movable.

Fig. 9 is a view similar to Fig. 7, but showing a modified form of cable sheave.

Now referring to the figures, and especially to Fig. 1, the invention will be described as applied to a conventional fly shuttle loom, but it is to be understood that it is applicable to all looms and that the description herein given is illustrative only. In Fig. 1 the loomsides 10 and 11 are interconnected by a plurality of girts, one lower girt 12 being shown, but it being understood that there are others. At the top front part of the loom there is provided a breast beam 13 resting at either end upon the loomsides, and, as will hereinafter be described in detail, this breast beam is so devised as to provide a support for bearings generally indicated by numerals 14 and 15 and attached to the end portions 20 of this beam, said bearings serving to support for rotation a pivot shaft 16. This pivot shaft 16, hereinafter termed a shaft and better shown in Fig. 2, serves to support the sand roll generally indicated by numeral 17 which is positively 25 rotated in any desired manner and which normally has a frictional surface of such nature as to advance the woven material passed thereabout and to draw it from the weaving point. This sand roll or fabric take-up roll is herein 30 comprised as a hollow structure being formed from relatively thin cylindrical tubing 18 which is secured in any convenient manner to hubs 19 and 20 adjacent the ends thereof. If desired, guide rolls adjacent the sand roll and positioned so as 35 to have the fabric passed about them and to increase the extent of contact between the fabric and sand roll may be used. These are well known to those skilled in this art.

These hubs are freely rotatable upon the shaft 40 16 or upon other bearing elements on that shaft, and one of the hubs, 19 according to the present construction, is extended outwardly and has a gear 21 affixed thereto by means of screws 22, or by other connecting means, many of which will 45 readily occur to those skilled in the art. This gear 21 in turn meshes with a pinion 23 keyed or otherwise secured to the end of a short spindle or shaft 24 guided within a bearing in the loom frame structure and driven through any 50 interconnecting means such as a gear train deriving movement from some one of the rotating parts of the loom, for example, the cam shaft or the crank shaft. It is to be understood that the gear train or other driving means is 55 capable of variation to alter within limits the relative rate of speed at which the sand roll 17 draws the fabric from the weaving point and therefore provides for the production of different types of woven material as is understood by those conversant with this particular art.

The cylindrical tube 18 may be attached to the hubs 19 and 20 in any satisfactory manner, for example, by press fitting or by some positive means such as screws. A novel method for 65 inserting and fixing the wooden or other plugs to which the fillet or sand roll covering is attached comprises first drilling and tapping holes into the tube and hubs after assembly. These holes are tapped on a taper as by a conventional pipe tap. The plugs are then screwed into these tapped holes very tightly and are cut and finished down to conform to the outer cylindrical surface of the roll. These plugs then serve as a means to which the ends of fillet F or other 70 rough surfaced material may be connected by

tacks or the like. Any suitable number of plugs is to be used and they are to be appropriately placed in the end or hub portions of the sand roll. The fillet is usually wound helically and in abutting relationship from one end to the other of the roll. The intermediate convolutions may, if desired, be secured to the tubing by cementing or in any other satisfactory way. In sand rolls which are not hollow as is that herein described, a number of spaced plugs are utilized, one for each convolution, more or less, of the fillet.

The cloth roll shaft 26 which actually comprises a steel or other shaft or core of sufficient diameter to support a roll of woven material 27 as the same is wound up upon being drawn from the weaving point, is supported at each end in bearings in blocks 28 and 29. These blocks, hereinafter referred to as bearing blocks, are vertically slidable along track members 30 and 31 which are attached in any suitable manner as by screws as indicated in Fig. 8 to vertical posts or stands 32 and 33. Each of these posts 32 and 33 is supported at its lower end on the girt 12 and at its upper end, is attached by suitable bolts or other means to the front depending portion 24, Figs. 4 and 5, of the breast beam 13.

One of these bearing blocks is illustrated in greater detail in the perspective view of Fig. 8 and each block has a T-shaped groove therein which is freely slidable along the track which is preferably comprised of two parts, the head 30' of that track or rail being bolted or screwed in place to facilitate fabrication. Each bearing block has an indentation or open bearing 35 therein within which the end of the shaft 26 rests.

Each of these bearing blocks is suspended from the shaft 16 upon which the sand roll also rotates, according to the preferred form of the invention, and preferably the suspending means comprises some flexible connector such as a steel cable. Steel cables 36 and 37 locked in their respective blocks extend upwardly and are correspondingly attached in some convenient manner to winding drums or sheaves which are themselves fixedly secured to the shaft. These sheaves may be provided with spirally or helically cut grooves and as shown more clearly in Figs. 2, 6 and 7, the cable 36 is wound about a sheave 38 fixed to the shaft 16 by a key 39 and having a groove 40 within which the cable is laterally guided or restrained. The helical groove 40 has a number of convolutions, depending upon the diameter of the sheave, to permit a sufficient length of cable to be wound up or extended therefrom so as to accommodate the maximum amount of movement necessary for raising and lowering the cloth roll shaft 26, that being largely dependent upon the maximum size of roll which it is contemplated will be wound on any particular loom. While a groove is preferably provided in each sheave, that may in instances be dispensed with and the cable wound upon a flanged drum or the like.

At the opposite end of the shaft 16 a corresponding sheave 41 has cable 37 connected thereto, and it is to be understood that these sheaves are preferably of opposite hand so that the cable winds from the inner end of each toward the outer end or vice versa, as the cloth roll shaft is elevated. That permits a symmetrical arrangement of parts and uniformity of motion with respect to a central, vertical axis. The axis of the cloth roll shaft is also according to the illustrated form of the device, disposed substantially

beneath the point at which the cables depart tangentially from their sheaves. However, the tracks upon which the bearing blocks move may be inclined, especially from front to rear of the loom as the said blocks move away from the sand roll thereby to provide for a larger roll of cloth without it extending too far toward the front of the loom. The cables are passed through holes formed in the bearing blocks as illustrated in Fig. 8 and, after being adjusted for length, are held or locked in place by means of a locking screw 42. A similar connecting means is employed at the sheaves as shown in Figs. 6 and 7, the cable being turned inwardly into a recess formed in the sheave and held by a corresponding locking screw 43. Any other convenient means of fixing the cables in these elements may be utilized.

Now referring to Figs. 1, 2, 3, 4 and 5, mechanism will be described the function of which is to elevate the cloth roll shaft or to lower it after a complete roll of fabric has been wound preparatory to removing that roll, and which also serves to bias the cloth roll upwardly toward the sand roll so that a sufficient pressure is developed between the surface of the sand roll and the fabric wound on the cloth roll shaft to assure winding of a tight and compact roll. Preferably the said cloth roll biasing mechanism is largely enclosed within the sand roll 17 and functions to impart to the shaft 16 a resiliently applied torque or twisting moment which always tends to wind the cables upon their sheaves.

First referring to Fig. 3, the modification, the parts which are identical with those similar parts shown in Fig. 2 have been given the same reference numerals. The distinction between the modification and the preferred form is largely confined to the spring which functions to impart the torque to the shaft 16 and the means by which that spring applies its force to the shaft. Since this is the simpler form it is described first. The hubs 19 and 20 of the sand roll are freely rotatable upon the shaft 16 in the case of the hub 19, and in the case of the hub 20, upon a bearing on bushing 44 rotatable on shaft 16 and to which is connected by means of suitable screws 45 or other means, a worm wheel 46. The worm wheel 46 has meshing therewith a worm 47 keyed to the inner end of a short shaft or spindle 48 to the squared end of which may be applied a crank 49, Figs. 4 and 5, this preferably being detachable as shown, although in some instances it may be permanently fixed to the spindle. The shaft 48 is carried in bearings 50 and 51 which comprise bosses extending inwardly from a mounting plate 52 which is bolted to the bottom face of the upper part of the breast beam 13, as illustrated in Figs. 4 and 5. This worm is preferably a single threaded worm and, at least should form a means for rotating the worm wheel and the bushing 44 irreversibly. Other irreversible drive means may be substituted.

A spring 53 surrounds shaft 16 and has one end 54 restrained within a drilled hole in the bushing 44 and its other end 55 similarly restrained in a collar 56 which is locked by means of a set screw 57 to the shaft 16. In actual operation of the device, the crank 49 is employed for raising the cloth roll shaft 26 preparatory to starting winding a fabric roll thereon, and in addition to raising that roll into contact with the sand roll, a predetermined amount of tension is placed in the spring 53 so that the pressure between the sand roll and the fabric on the

Cloth roll closely approximates that necessary for proper winding of a tight and relatively solid roll of material.

As the size of the fabric roll increases, the cloth roll shaft is naturally forced downwardly or away from the sand roll and that in turn moves the bearing blocks 28 and 29 downwardly a corresponding distance to draw the cables from their sheaves and since the latter are keyed to shaft 16, to rotate that shaft throughout a corresponding angular extent. The rotation of shaft 16 causes a further tightening of the spring 53, but that is to an extent compensated by the additional weight of the fabric on the cloth roll. It is intended that the spring 53 shall be of sufficient strength and shall have a sufficient length so that after an initial setting of the device, a complete roll may be wound without further attention to the adjustment of the parts. Obviously, when a maximum amount of material has been wound on the cloth roll, the crank 49 is then employed to relax tension in spring 53 and to lower the cloth roll into some suitable conveyance by which it may be removed. The remaining tension in the spring is then removed so that the cloth roll shaft is freed from its bearings 35 whereupon the full roll may be removed and a new shaft inserted. The operating crank is so positioned that the operator may turn it while in normal standing position and thus all adjustments effected thereby are accomplished with a minimum of effort.

Now referring to Fig. 2, the preferred form of the invention includes not only a resilient means by which the cloth roll is normally maintained in contact with the sand roll under a predetermined amount of pressure, but, in addition, a clutch introduced into the combination and which serves in combination with the other parts to permit the gradual lowering of the cloth roll as the package is increased in size, either without any change in the amount of tension placed upon the spring, or where tension in the resilient means is increased, to prevent excessive tension therein by adjusting the clutch to slip under a predetermined load at some later point in the winding of a roll of material. Under the first mentioned setting, the clutch is so adjusted that it does not slip under the greatest weight of cloth roll which may be wound, but will not impose more pressure between the fabric and sand roll at the termination of winding than is necessary to assure proper traction. There is thus no possibility of over-tensioning the spring and therefore it is not necessary to guard against that contingency as the cloth roll is initially set preparatory to starting winding thereon, or later as the roll builds to size. The spring may be tensioned only to whatever predetermined degree is possible in accordance with the clutch setting so that the crank employed in raising the cloth roll shaft may be turned until contact is made between the roll shaft and sand roll and then rotation of the crank continued for a few turns sufficient to impose that amount of tension required in the spring after which the slipping of the clutch may be felt. Even if that is not possible or if no attention is paid to the point at which the clutch starts to slip, no excess tension is possible of being placed upon the spring and therefore this form of the invention serves to guard against undue pressure between the fabric on the cloth roll shaft and the sand roll surface at the very start or at any point in the building of the cloth roll. In prior practice, if too much pressure were imposed at

the start of winding, the increase in size of the package then tensioned the spring a further amount and excess tension existed all through the winding of the package until a point of extreme tension was reached, even though the spring were of considerable length, sometimes causing rupture of the fabric and/or spring breakage. In fact, that is just the reverse of what is desired since it is more important to have slightly more pressure between the fabric and the sand roll at the start of winding than after a sizable package has been completed since as the diameter of the wound material increases, the effective area of contact between the two cylindrical surfaces is increased.

According to the second mentioned mode of operation of the preferred form, the spring should be somewhat longer and the clutch set to slip only after considerable winding has taken place. Then the first part of the roll is formed as the spring gradually increases in tension, while the later part, after the clutch starts to slip, is wound, as pressure at the contacting surfaces decreases due to increasing weight of the cloth roll.

The clutch which functions to permit slipping as the spring tension tends to exceed some prescribed value includes a member 58 rotatable on shaft 16, but prevented from moving axially thereof by a collar 59 and thrust bearing 60 interposed between the collar which is set screwed to the shaft, and a shoulder formed within the clutch member itself. The other part 61 of the clutch is keyed for rotation with the shaft 16, but is permitted limited sliding movement lengthwise of that shaft. A key 62 is fixed within the shaft, but relatively slidable in the cooperating keyway in the clutch member. As herein illustrated, it is preferred that the clutch interengaging surfaces be of conical form, although it is to be understood that other types of clutches may be employed and in that event the mechanism is to be modified accordingly. A facing 63 is preferably cemented or otherwise attached to the clutch member 61, although, if desired, the facing may be fixed to the outer clutch part, or may float between the two members.

The clutch part 61 is pressed into engagement with the cooperating member 58 by means of a spring 64 maintained under a suitable amount of compression by a collar 65 adjustably set in a desired position along shaft 16. It is not necessary to provide any great amount of compressive force within this spring since the conical type clutch makes available considerable driving force without the application of more than a reasonable amount of axial pressure forcing the two parts into engagement. Wear in the clutch is compensated by the spring 64.

A spring 66 surrounds shaft 16 and has one end 67 restrained in the bushing 44 and the other end 68 similarly restrained within the otherwise freely rotatable clutch part 58. This spring is considerably shorter than the spring 53, Fig. 3, and does not need to be of greater length than is necessary for permitting a small amount of deflection resiliently to press the fabric roll against the sand roll after contact has been made.

In most instances the increase in weight of the fabric roll as it approaches maximum diameter makes little difference, or at least, does not make a sufficient difference, so that there is any difficulty experienced due to the fact there is no compensating increase in the amount of torque which may be conveyed through the clutch. The fact that less pressure between the surface of the fabric roll and the sand roll is necessary as the roll

increases in size more or less compensates for the fact that the additional weight would tend to relax some of the pressure at the surfaces in contact.

However, according to a modified form of cable sheave shown in detail in Fig. 9, it is contemplated that compensation be provided for the above mentioned contingency if that additional refinement is required. In the modified sheave, each cable is wound about the periphery and rests in a groove which gradually decreases in effective radius from one end of the sheave to the other. The cable groove is, therefore, cut or otherwise formed along a helix of decreasing radius from one end to the other.

The sheave 69 keyed to shaft 16' by means of a key 39' has a continuous groove 70 formed therein within which the cable 36' is adapted to be retained. Here the radius of the groove is a maximum at the end of the sheave at which the cable passes tangentially from the groove when the cloth roll is in uppermost position. Then as the roll increases in diameter and the weight increases correspondingly, the effective radius of the sheave decreases to become a minimum when the roll is completed. That assures that the moment arm at which the cable functions is correspondingly less as the weight depended from the cable increases so that there is a tendency to balance these functions in such manner that a reasonably uniform pressure or a substantially uniform winding force is exerted on the fabric where it contacts the sand roll at all times. The actual radius at the largest and at the smallest ends of the sheaves will vary depending upon the total increase in weight plus pressure from relatively empty to a full fabric roll and upon other factors. It is to be understood that the setting of the clutch is such that without any compensation a relatively wide range is provided within which a well wound cloth roll is produced.

In most cases the effective radius may vary uniformly from a maximum to a minimum, but in instances where it is desired to take into consideration all variables involved and to provide for a fairly uniform value of torque applied at the shaft 16', the most advantageous curve (probably a functional one) may be calculated or otherwise determined. The sheaves are then to be designed accordingly with the radii of their cable grooves or other surfaces upon which the cables are wound conforming to values established as above indicated.

Assuming all parts are properly adjusted, the operator merely has to insert an empty cloth roll shaft in the bearing blocks and by means of the crank 49 elevates that shaft until it contacts the sand roll, having first started the fabric around the shaft so that it may thereafter be wound as the weaving progresses. In one instance the hand crank is employed with that form of the invention shown in Fig. 2 to tension the spring 66 until the clutch actually slips as above described. With the modification of Fig. 3 the longer spring 53 is tensioned in accordance with judgment exercised by the operator. Then as weaving progresses, the fabric is wound upon the shaft 26 and as the fabric roll 27 increases in size, the cables 36 and 37 are drawn downwardly thereby rotating the shaft 16 through the sheaves 38 and 41. It is to be understood that the rotation of the sand roll accomplished through pinion 23 and gear 21 is unaffected by and has no direct effect upon the function of the shaft 16 or parts carried thereby since that

shaft merely forms a supporting bearing for the sand roll itself.

In the form of invention shown in Fig. 2, continued downward movement of the shaft 26 and bearing blocks 28 and 29 tends to rotate the clutch member 58 and to increase tension in spring 66 which is held at one end by the attached bushing 44 and the gear and worm assembly, but it is obvious that that increase in tension will only continue until the clutch surfaces start to slip. In actual practice there is a more or less continuous and gradual slipping between the clutch surfaces and the spring 66 is actually maintained under more or less even tension.

The above mentioned operation of the parts continues until a fabric roll of prescribed diameter has been wound. Upon completion of the roll, it is only necessary to employ the crank again and to rotate the bushing 44 first releasing part of the tension in the spring 66 and thereafter winding the roll downwardly as much as is necessary to lower the fabric roll upon a conveying or other receiving means to permit ready removal of the shaft 26 from the bearings in the blocks 28 and 29, and then further relieve the remaining tension in the spring 66. That requires a minimum of effort and much less time than is required where no clutch is employed. In the latter case, not only must the cloth roll be lowered, but it is also quite essential that all of the tension be removed from the relatively long, highly tensioned spring since it will otherwise be impractical to remove the cloth roll shaft 26; when the weight is taken off the bearing blocks 28 and 29, they will immediately rise if any tension still remains in the spring. The position of the crank at the level of the breast beam, however, makes it much easier to perform these functions whenever a new roll is to be started or whenever a completed cloth roll is to be removed. It will be noted that after all tension has been relieved in the spring 66, further rotation of the crank will allow the blocks to be lowered by gravity, thereby automatically releasing the cloth roll shaft from the loom.

The operation is varied somewhat where the clutch is not set to slip until the fabric roll has been partially wound. There the initial setting of the spring which may be appreciably longer than that shown in Fig. 2, is so adjusted that only a minimum of contact pressure is provided. Then the clutch is assumed to have been adjusted to slip at a point where the cloth roll has been partially wound, and from that point on the spring tension remains nearly constant and the increase in roll size is compensated through slippage of the clutch.

While it is preferred that the clutch and spring mechanism be enclosed within the sand roll 17, it is possible to employ an independent shaft for the sand roll and to separate therefrom the spring shaft mechanism including the spring, clutch, sheaves and cables and to mount them all on a separate shaft controlled in a similar manner by a crank adapted to rotate a worm and gear mechanism on that separate shaft. That involves additional mechanism, but may in some instances be employed to convert older machines to the use of the present spring shaft and cloth roll shaft supporting and operating means if so desired.

Throughout the specification and claims the terms "cloth roll" and "fabric roll" have been employed to designate the woven material wound upon the "cloth roll shaft" which is intended to

comprise the core upon which fabric is wound, one example of which is apparent at 26. The "sand roll" is well known in the art and is sometimes referred to as a fabric take-up roll. The terms "supporting shaft" and "spring shaft" apply to that shaft 16 or an equivalent thereof which, in the preferred form of the invention, serves the dual function of rotatably mounting the sand roll and also for supporting the cloth roll shaft and the mechanism incidental to biasing that shaft upwardly to establish pressure contact between the fabric and the sand roll. As stated these functions may in cases be separated between two shafts.

While a particular type of clutch and specific arrangement thereof has been disclosed in detail the general arrangement may be varied and, to an extent, reversal of the fixed and relatively movable elements is contemplated.

While one embodiment and certain modifications of the invention have been disclosed, it is to be understood that the inventive concept may be carried out in a number of ways. The invention is, therefore, not to be limited to the precise details described, but it is intended to embrace all variations and modifications thereof falling within the spirit of the invention and the scope of the claims.

I claim:

1. In a loom the combination of a hollow sand roll and a cloth roll shaft upon which the woven fabric is wound as it is advanced by the sand roll, a common shaft for rotatably supporting the hollow sand roll and from which the said cloth roll shaft is suspended, and a resiliently applied biasing means enclosed within said sand roll for the said common shaft for urging it in a direction to draw the suspended cloth roll shaft and fabric thereon toward the sand roll.

2. In a loom the combination of a sand roll and a cloth roll shaft upon which the woven fabric is wound as it is advanced by the sand roll, a pivot shaft on which said sand roll is positively rotated, bearing blocks for said cloth roll shaft and guide means upon which said blocks move to and from the sand roll, flexible connecting means attached to each block and means fixed for rotation with said shaft and about which the said flexible connecting means are passed to be extended or retracted as the shaft is rotated, and resilient biasing means connected to said shaft for imparting a biasing torque to it for drawing the flexible connecting means and the cloth roll shaft toward the sand roll to press fabric wound on the cloth roll shaft tightly against that roll.

3. In a loom the combination of a sand roll and a cloth roll shaft upon which the woven fabric is wound as it is advanced by the sand roll, a pivot shaft on which said sand roll is positively rotated, bearing blocks for said cloth roll shaft and guide means upon which said blocks are mounted for sliding movement to and from the sand roll, a flexible cable attached to each block and a sheave fixed to the said shaft for rotation therewith and in alignment with each bearing block, to which the flexible cable extending from the bearing block is attached and about which it is wound, and a resilient biasing means connected to said shaft for imparting to it and the sheaves a biasing torque for drawing the cloth roll and cables toward the sand roll to press fabric wound on the cloth roll shaft tightly against that roll.

4. In a loom the combination of a sand roll

and a cloth roll shaft upon which the woven fabric is wound as it is advanced by the sand roll, a pivot shaft on which said sand roll is positively rotated, a suspension means carried by said shaft and connected to said cloth roll shaft, a resilient biasing means enclosed within said sand roll and attached at one end to said shaft and means for restraining the opposite end of said resilient biasing means comprising a rotatable member projecting externally of the sand roll and means for adjusting the relative position of said restraining means and for maintaining it in an adjusted position thereby to vary the tension in the resilient means, said resilient means being effective when tensioned for imparting a biasing torque to the shaft for drawing the cloth roll toward the sand roll to press fabric wound on the cloth roll shaft tightly against that roll.

5. In a loom the combination of a sand roll and a cloth roll shaft upon which the woven fabric is wound as it is advanced by the sand roll, a pivot shaft on which said sand roll is positively rotated, suspension means carried by said shaft and connected to said cloth roll shaft and a resilient biasing means connected to said pivot shaft for imparting to it a biasing torque for drawing the cloth roll shaft and the suspension means toward the sand roll to press the fabric wound on the cloth roll shaft tightly against that roll, said resilient biasing means comprising a clutch member one element of which is fixed for rotation with the said shaft, said other clutch element being freely rotatable upon the shaft, a spring having one end attached to said other clutch element, gear means on said shaft, the other end of said spring being connected to said gear means, and means for rotating said gear to vary the tension in said spring, to rotate said shaft and the suspension means carried by the shaft to position the cloth roll differently in relation to the sand roll, said means further being effective for locking the said gear in an adjusted position.

6. In a loom the combination of a sand roll and a cloth roll shaft upon which the woven fabric is wound as it is advanced by the sand roll, a pivot shaft on which said sand roll is positively rotated, a suspension means carried by said shaft and connected to said cloth roll shaft comprising a sheave fixed adjacent each end of the shaft, bearing blocks in one of which each end of the cloth roll shaft is rotatively supported and a flexible cable attached to each bearing block and to its sheave for being wound on the latter as the shaft is rotated, and resilient biasing means connected to said shaft for imparting to it a biasing torque for drawing the cloth roll and the suspension means toward the sand roll to press fabric wound on the cloth roll shaft tightly against that roll, said resilient biasing means comprising a clutch carried by said shaft and enclosed within said sand roll, one element of said clutch being keyed to said shaft for rotation therewith, the other element of said clutch having attached thereto one end of a spring, the other end of said spring being fixed within a gear rotated and restrained member on said shaft and extending externally of the sand roll, and means meshing with the gear for maintaining the member in an adjusted position and for rotating the shaft through the clutch thereby to permit the cloth roll to be moved away from the sand roll which means includes a worm, a spindle to which said worm is fixed and a crank attachable to said spindle to permit manual operation thereof.

7. In a loom the combination of a sand roll and a cloth roll shaft upon which the woven

fabric is wound as it is advanced by the sand roll, a pivot shaft on which said sand roll is positively rotated, bearing blocks for said cloth roll shaft and guide means upon which said blocks are mounted for sliding movement to and from the sand roll, a flexible cable attached to each block and a sheave fixed to the said shaft for rotation therewith and in alignment with each bearing block, to which the flexible cable extending from the bearing block is attached and about which it is wound, said sheave having a helical groove therein within which the cable is guided, the effective radius of said groove from the center of the sheave being decreased from one end thereof to the other thereby to decrease the moment arm at which the cables act as the weight of fabric wound on the cloth roll shaft increases, and a resilient biasing means connected to said shaft for imparting to it and the sheaves a biasing torque for drawing the cloth roll toward the sand roll to press fabric wound on the cloth roll shaft tightly against the sand roll.

8. In a loom the combination of a cloth roll shaft, a stand in which said cloth roll shaft is movable and by which it is guided, a supporting shaft having means thereon from which said cloth roll shaft is suspended, and means by which said supporting shaft is biased in a direction to elevate the cloth roll shaft, including a spring fixed at one end to the supporting shaft, a relatively rotatable member carried by the supporting shaft by which the other end of said spring is restrained and manually operated means for positioning said member and for locking it in an adjusted position.

9. In a loom the combination of a cloth roll shaft, a stand in which said cloth roll shaft is movable and by which it is guided comprising a guide rail adjacent each end of the roll and a bearing block slideable on each rail, a supporting shaft having a sheave fixed adjacent each end and in substantial alignment with the bearing blocks, flexible connectors passed about the sheaves and attached to said blocks, and means by which said supporting shaft is biased in a direction to elevate the cloth roll shaft, including a spring fixed at one end to the supporting shaft, a relatively rotatable member carried by the shaft by which the other end of said spring is restrained and manually operated means for positioning said member and for locking it in an adjusted position.

10. In a loom the combination of a cloth roll shaft, a stand in which said cloth roll shaft is movable and by which it is guided comprising a guide rail adjacent each end of the roll and a bearing block slideable on each rail, a supporting shaft having a sheave fixed adjacent each end and in substantial alignment with its respective bearing block, a flexible cable passed about each sheave and attached thereto at one end and connected at the other end to the aligning block, and means by which said supporting shaft is biased in a direction to elevate the cloth roll through the said cables, said means including a collar fixed to said supporting shaft, a spring concentrically disposed about said shaft and having one end restrained in said collar, a worm gear rotatable on the shaft by means of which the other end of said spring is restrained, a worm meshing with said worm gear, a projecting shaft fixed to said worm and crank means for manually rotating the worm for tensioning said spring and for releasing tension thereon substantially as is described.

11. In a loom the combination of a cloth roll shaft, a stand in which said cloth roll shaft is movable and by which it is guided comprising a guide rail adjacent each end of the roll and a bearing block slideable on each rail, a supporting shaft having a sheave fixed adjacent each end and in substantial alignment with the bearing blocks, a flexible cable passed about each sheave and attached thereto at one end and connected at the other end to its respective block, and means by which said supporting shaft is biased in a direction to elevate the cloth roll shaft, said means comprising a clutch carried by the shaft, one element of said clutch being fixed for rotation with the shaft and the other clutch element being freely rotatable on the shaft, a spring having one end attached to said other clutch element, a rotatable member carried by the shaft within which the other end of said spring is retained and a manually operated means for positioning said member and for retaining it in an adjusted position.

12. In a spring shaft mechanism functioning upon a cloth roll shaft to press fabric wound thereon into contact with a sand roll, a means for resiliently applying a biasing torque to said spring shaft comprising engaging clutch members one of which is fixed for rotation with said spring shaft and the other of which is freely rotatable upon said shaft, a gear freely rotatable on the shaft, an extension from said gear, a spring surrounding the shaft between the freely rotatable clutch member and the extension from said gear and having one end restrained in the clutch member and the other end in the extension, and a manually operated means for changing the relative position of the gear and locking it in an adjusted position.

13. In a spring shaft mechanism functioning upon a cloth roll shaft to press fabric wound thereon into contact with a sand roll, a means for resiliently applying a biasing torque to said spring shaft comprising engaging clutch members one of which is fixed for rotation with but slideable along said spring shaft and the other of which is freely rotatable upon that shaft, means for preventing axial movement of the said freely rotatable clutch member and a spring means for pressing the first mentioned clutch member into engagement with the second, a gear freely rotatable on the shaft and a spring surrounding the shaft between the second clutch member and the gear and having one end restrained in the said second clutch member and the other end by the gear, and a manually operated means for changing the relative position of the gear and locking it in an adjusted position.

14. In a spring shaft mechanism functioning upon a cloth roll shaft to press fabric wound thereon into contact with a sand roll, a means for resiliently applying a biasing torque to said shaft comprising clutch members having conically formed, engaging, frictional surfaces, one said clutch member being restrained from rotation relatively to the shaft but provided for axial movement thereon, the other said clutch member being freely rotatable upon said shaft, means for restraining the said other clutch member from axial movement along the shaft, spring means for pressing that clutch member which is axially movable along the shaft toward the second mentioned member thereby to engage the frictional surfaces, a worm gear freely rotatable on the shaft and a spring surrounding the shaft between the said second mentioned clutch member and the worm gear and having one end re-

strained in the clutch member and the other end in the gear, a worm engageable with said gear and manually operated crank means for rotating said worm to change the relative position of the gear and to lock it in an adjusted position.

15. In a loom the combination of a hollow sand roll and a cloth roll shaft upon which woven fabric is wound as it is advanced by the sand roll, a common shaft for rotatably supporting the hollow sand roll and from which the said cloth roll shaft is suspended, a resiliently applied biasing means enclosed within the hollow sand roll and attached to the common shaft for applying torque to the shaft in a direction to draw the suspended cloth roll shaft and fabric thereon toward the sand roll, and a means carried by the common shaft to which the biasing means is also attached for restraining an end of the biasing means and for manually adjusting the effect of that means.

16. In a loom the combination of a sand roll and a cloth roll shaft upon which woven fabric is wound as it is advanced by the sand roll, a pivot shaft on which said sand roll is positively rotated, bearing means in which said pivot shaft is independently rotatable, suspension means carried by said shaft and connected to said cloth roll, said suspension means being taken up or
